COMBINED TABLE AND CHAIRS

Bernard B. Murtaugh, Philadelphia, Pa.

Application October 1, 1948, Serial No. 148,908

Term of patent 7 years

(Cl. D33—14)

To all whom it may concern:

Be it known that I, Bernard B. Murtaugh, a citizen of the United States, residing at Philadelphia, in the county of Philadelphia and State of Pennsylvania, have invented a new, original, and ornamental Design for a Combined Table and Chairs, of which the following is a specification, reference being had to the accompanying drawing, forming a part hereof.

In the drawings, Fig. 1 is a perspective view of a combined table and chairs, showing my new design, and Fig. 2 is a perspective view of the same, on a reduced scale, and with the stools extended.

I claim:

The ornamental design for a combined table and chairs, as shown.

BERNARD B. MURTAUGH.
